UNITED STATES PATENT OFFICE.

CHARLES R. WEBER, OF SPRINGFIELD, OHIO, ASSIGNOR TO THE RIDGELY TRIMMER COMPANY, OF SPRINGFIELD, OHIO, A CORPORATION OF WEST VIRGINIA.

PAPER-CUTTER.

No. 802,720.

Specification of Letters Patent.

Patented Oct. 24, 1905.

Application filed November 23, 1903. Serial No. 182,348.

To all whom it may concern:

Be it known that I, CHARLES R. WEBER, a citizen of the United States, residing at Springfield, in the county of Clark and State of Ohio, have invented certain new and useful Improvements in Paper-Cutters, of which the following is a specification.

My invention relates to improvements in paper-cutters, and particularly to that class of paper-cutters which are used for trimming wall-paper, &c.

The object of my invention is to simplify and cheapen the construction of devices of this kind and also to provide a device which will be more efficient in operation than the ones heretofore employed.

In the accompanying drawings, Figure 1 is a perspective view of a device embodying my invention shown in position on a straight-edge in connection with which it is used. Fig. 2 is a rear elevation of the device shown removed from the straight-edge. Fig. 3 is a vertical sectional view taken on the line $\alpha\alpha$ of Fig. 2. Fig. 4 is a front elevation of the gage. Fig. 5 is an end elevation of the device shown in position on the straight-edge.

Like parts are represented by similar characters of reference in the several views.

In the said drawings, a represents the main frame of the device, which is recessed, as shown at a' , on its rear side for the reception of the cutting-disk b and is provided with a forwardly - extending boss a^2 . This boss a^2 and the central portion of the frame a are bored out and screw-threaded to receive the screw-threaded end of an arbor c , upon which the cutting-disk is mounted and adapted to revolve, the said disk being held in position against a small boss a^3 on the inner face of the frame by means of a collar c' on the said arbor, or, if desired, instead of the boss a^3 a washer may be interposed between the disk and frame. The arbor c is extended rearwardly from said collar c' for a suitable distance and is extended through a slot d' of a gage d , said arbor being provided at its rear end with a head c^2 , the said gage being fitted between said collar and head and held in position thereby. The said head is grooved, as shown, to receive a screw-driver for tightening up the parts in assembling the device.

Secured to the upper portion of the gage d is a spring e , the said spring being extended in opposite directions to the ends of the tool

and adapted to bear on the under sides of 55 rearwardly - projecting portions a^4 of the frame, said portions a^4 being suitably formed on their upper surfaces to provide a convenient means for grasping the tool in operation.

The respective ends of the gage d are enlarged and provided with downwardly-projecting flanges d^2 d^3 , each of said flanges d^2 having at its lower end a rearwardly-projecting lip d^4 . The respective ends of the main frame a are formed with straight faces a^5 , 65 and the said flanges d^2 and that portion of the gage from which said flanges extend are also formed with straight guiding-faces d^6 , the said frame being adapted to fit snugly between said gage-faces, but adapted to move 70 freely between the same, which form guides therefor, the said gage and its flanges d^2 being extended forwardly at this point, so as to stand substantially flush with the outer or front surface of the frame. 75

The straight-edge which I employ is represented at f and has on its upper surface a groove f' to receive the flange d^3 of the gage and has also on its forward edge a groove f^2 to receive the lips d^4 of the flanges d^2 . The 80 said straight - edge between the respective grooves f' and f^2 is provided with the usual metal reinforcing-strip f^3 .

It will be seen from the construction described that I have provided a cutting-tool 85 which is very simple in construction and yet efficient in operation. The arbor not only supports the cutting - disk, but also provides a means for holding the main frame and gage together and also forms a stop for the main 90 frame in its upward movement under the action of the spring. The boss a^2 also serves as a handle for operating the tool in connection with the portions a^4 of the frame, and the arrangement and construction permit the 95 tool to be used either by a right or left handed operator. If desired, the screw-threaded portion of the arbor can be extended through the rear end of the boss to receive a locking-nut to prevent the arbor from turning. 100

Having thus described my invention, I claim—

1. In a cutting-tool, the combination of a main frame, a gage, and a cutting-disk, of an arbor forming the support for said disk and 105 also forming the means for connecting said frame and gage movably together, substantially as specified.

2. In a cutting-tool, a gage having guiding-faces thereon, a frame mounted between said guiding-faces, an arbor on said frame carrying a cutting-disk, said arbor forming the means for connecting said gage and frame together but permitting a movement of said frame with relation to said gage, substantially as specified. 35
3. In a paper-cutter, a main frame, an arbor in said frame, a cutting-disk mounted on said arbor, and a gage provided with a slotted opening, said arbor being extended through said slotted opening to form a sliding connection between said frame and gage and also to form a stop for said frame in its movement in one direction, and a spring between said gage and frame, substantially as specified. 40
4. In a cutting-tool, a main frame, an arbor therein, a cutting-disk mounted on said arbor, a gage secured to said frame by means of said arbor, the connection being such as to permit a vertical sliding movement of said frame and arbor with relation to said gage, said gage forming a stop for said arbor in its upward movement, guiding-faces at the ends of said gage for said frame, and a spring between said frame and gage, substantially as specified. 45
5. In a cutting-tool, a main recessed frame, a fixed arbor therein, a cutting-disk mounted on said arbor within the recess of said frame, a collar on said arbor to hold said disk in position, a gage having a slotted opening through which said arbor extends, a head on said arbor to hold said frame in position on said gage, a spring between said gage and frame, and guiding-faces on said gage for said frame, substantially as specified. 50

6. In a cutting-tool, a straight-edge, the groove f' on the upper surface of said straight-edge and the groove f^2 on the outer edge of said straight-edge, a gage having a downwardly-projecting flange to fit in said groove f' , and also having a downwardly-projecting flange formed with a laterally-extending lip which fits in the groove f^2 , a cutter-carrying frame slidably connected to said gage, said gage having straight guiding-faces for said frame to cause a straight vertical movement of said frame within said gage, and a spring between said gage and frame, substantially as specified. 55

In testimony whereof I have hereunto set my hand this 18th day of November, A. D. 1903.

CHARLES R. WEBER.
